Henry F. Brewington,
ATTORNEY.

UNITED STATES PATENT OFFICE.

JAMES A. KNOWLES, OF BALTIMORE, MARYLAND.

UNIVERSAL-JOINT PULLER.

1,337,233.

Specification of Letters Patent. Patented Apr. 20, 1920.

Application filed June 18, 1919. Serial No. 305,115.

To all whom it may concern:

Be it known that I, JAMES A. KNOWLES, a citizen of the United States, residing at Baltimore city, State of Maryland, have invented certain new and useful Improvements in Universal-Joint Pullers, of which the following is a specification.

This invention relates to devices for disengaging a shaft from a part through which 10 said shaft passes where said part is tightly fitted on the shaft. The device has been designed more particularly for separating a shaft from one half of a universal joint, although it is not limited to such use but 15 may, with equal facility, be employed for separating other parts or elements.

The invention has for its object to provide a very simple and highly efficient device of the kind stated, and also one which can be 20 easily applied and removed, and which is rapid and sure in operation.

The object stated is attained by means of a novel combination and arrangement of parts to be hereinafter described and 25 claimed, and in order that the same may be better understood, reference is had to the accompanying drawing forming a part of this specification.

In the drawing,

30 Figure 1 is a longitudinal section showing the manner in which the device is used;

Fig. 2 is a cross-section on the line 2—2 of Fig. 1, and

Fig. 3 is an elevation of the device.

35 Referring specifically to the drawing, 5 denotes a fragment of a shaft which is flexibly connected to another shaft (not shown) by a universal joint. The section of the joint to which the last mentioned 40 shaft is connected is shown at 6, and it is tubular to receive said shaft. It will also be noted that the section 6 has a series of internal longitudinal ribs 7 by which the shaft is splined to the section to permit relative 45 longitudinal movement of the parts but not a relative rotary movement, the parts turning together. As this is a well known expedient, a further description thereof is not necessary, it being understood that the 50 shaft is longitudinally grooved to seat the ribs 7.

The section of the universal joint which

is attached to the shaft 5 is shown at 8. This shaft extends completely through the section so that one end is opposite the inner end 55 of the section 6, and upon bringing the section 6 into alinement with the shaft 5 as shown in Fig. 1, after removal of the shaft of the section 6, the device can be applied for effecting the separation of the shaft 5 60 from the part 8.

The device for effecting the separation of the shaft 5 from the part 8 comprises a nut 9 and a screw 10 threaded therethrough. This nut is inserted into the hollow of the 65 section 6 and in order to prevent it from turning therein, it is formed with splines 11 matching the splines 7 of said section. It will therefore be evident that if the nut is also held against longitudinal movement, the 70 screw 10 will be caused to travel through the same when it is turned. The outer end of the screw has a head 12 for the application of a wrench or other tool to turn the same. The other end of the screw is adapt- 75 ed to abut against the end of the shaft 5 as shown in Fig. 1.

When the screw 10 is advanced toward the shaft 5, the latter is forced back out of the universal joint section 8. The end thrust 80 on the nut 9 is taken up by making its inner end in the shape of a collar 13. The diameter of this portion of the nut is such that when it comes against the inner end of the section 8 it is prevented from enter- 85 ing the same by the ends of the ribs or splines 7 of the latter. The nut will be inserted into the section 8 from the inner end thereof, its splined portion 11 freely enter- 90 ing the same, and when the collar 13 en- gages the end of the section, further inward movement of the nut is prevented. The nut can be inserted by turning the part 6 side- wise to expose its inner end.

The nut is now prevented from rotating in 95 the section 6 and the engagement of the collar 13 with the inner end of the latter prevents further inward movement of the nut and thus takes up the end thrust when the screw 10 is operated as hereinbefore 100 described to push the shaft 5 out of the universal joint section 8.

The device is strong and durable, it can be easily and quickly applied and removed,

and it will effect separation of the parts 5 and 8 no matter how tightly they are wedged together.

I claim:

- 5 A device of the character described comprising a nut which is externally splined to prevent its rotation in a member adapted to receive and support the same, and a screw threaded through the nut and adapted when
- 10 advanced to force one element off another,

one end of the nut having a collar to abut against one end of the aforesaid member to take up the end thrust on the nut when the screw is advanced.

In testimony whereof I affix my signature 15 in the presence of two witnesses.

JAMES A. KNOWLES.

Witnesses:
